PRIMING MIXTURE

James E. Burns, Bridgeport, Conn., assignor to
Remington Arms Company, Inc., a corpora-
tion of Delaware

No Drawing. Application May 26, 1931
Serial No. 540,196

11 Claims. (Cl. 52—4)

This invention relates to priming mixtures, particularly to priming mixtures of the non-corrosive type, and contemplates the use of certain recently discovered salts as priming mixture 5 fuels.

Ammunition priming mixtures as ordinarily made comprise three classes of ingredients: a fuel, or substance to be oxidized; an oxidizer, to furnish the oxygen necessary for the oxidizing of 10 the fuel; and, a combustion initiator, having the function of starting the reaction between the fuel and the oxidizer. It is not necessary that either the fuel or the oxidizer in themselves be subject to decomposition under the stimulus 15 of a blow. The combustion initiator, however, must be sensitive to shock, its decomposition being productive of sufficient heat and pressure to cause reaction between the oxidizer and fuel. Present day conditions add the requirement that 20 no ingredient of the mixture leave a corrosive residue. This requirement greatly restricts the field of usable priming materials, and gives rise to peculiar problems. The available non-corrosive oxidizers are acidic in character, and 25 tend to produce an acidic condition in the mixture which may be detrimental to stability, in that it promotes a reaction between certain commonly used combustion initiators and a common fuel. A fuel which does not tend to react 30 with the combustion initiator in the presence of weak acids is therefore most desirable.

The present invention comprises the discovery that certain recently found salts of a derivative of salicylic acid are excellent priming mixture fuels and possess extraordinary stability 35 characteristics. They are the salts of dinitrosalicylic acid, and particularly the lead salts thereof. These lead salts have been but recently discovered. The normal salt has the composition $C_6H_2(NO_2)_2OCOOPb$, and analysis of a basic salt which has been produced indicates its composition to be $C_6H_2(NO_2)_2OPbOHCOOPbOH$. While either of these salts constitutes a desirable 40 priming mixture fuel, the normal salt is preferred. Desirable results have been secured by the use of this salt in conjunction with such combustion initiators as mercury fulminate; a mixture of mercury fulminate and lead styphnate; lead styphnate alone; mixtures of lead styphnate 45 and guanylinitrosaminoguanylterracene; basic lead picrate; basic lead picrate with guanylinitrosaminoguanylterracene; diazodinitrophenol; diazodinitrophenol with basic lead picrate; and diazodinitrophenol with lead styphnate; and with 50 such oxidizers as lead nitrate, basic lead nitrate, and 55 such oxidizers as lead nitrate, basic lead nitrate,

and barium nitrate. Admixtures of other fuels, such as antimony sulphide and calcium silicide, are sometimes desirable.

A typical mixture utilizing mercury fulminate 60 as a combustion initiator is as follows:

Mercury fulminate	40%
Barium nitrate	29
Normal lead dinitrosalicylate	10
Glass	20
Gum	1
	65

It is sometimes desirable to add to such mixtures varying amounts of lead styphnate. Such 70 mixtures are as follows:

Mercury fulminate	25%	to 40%	preferably 25%
Lead styphnate	5	to 10	preferably 8
Barium nitrate	24	to 44	preferably 44
Antimony sulphide	0	to 16	preferably 16
Normal lead dinitrosalicy- late	4	to 10	preferably 7
Glass	0	to 30	75

Typical mixtures including basic lead picrate and diazodinitrophenol as combustion initiators 80 are as follows:

Basic lead picrate	30%	to 38%
Diazodinitrophenol	5	to 10
Lead nitrate	25	to 36
Normal lead dinitrosalicylate	5	to 10
Antimony sulphide	0	to 15
Calcium silicide	0	to 5
	85	

Mercury fulminate mixtures utilizing basic lead 90 dinitrosalicylate are as follows:

Murcury fulminate	35%	to 40%
Lead styphnate	0	to 5
Barium nitrate	24	to 30
Basic lead dinitrosalicylate	5	to 10
Glass	20	to 30

A non-fulminate mixture utilizing basic lead 100 dinitrosalicylate is

Lead styphnate	30%
Guanylinitrosaminoguanylterracene	2
Basic lead nitrate	30
Basic lead dinitrosalicylate	13
Glass	25
	105

All of the foregoing formulas, however, are 110

merely typical, and are to be understood as illustrative, and not restrictive, the invention being fundamental in character and limited only by a broad interpretation of the appended claims.

5 What is claimed is:

1. A priming mixture for ammunition containing a lead salt of dinitrosalicylic acid.

2. A priming mixture containing a normal lead salt of dinitrosalicylic acid.

10 3. A priming mixture for ammunition containing a basic lead salt of dinitrosalicylic acid.

4. A priming mixture containing a lead salt of dinitrosalicylic acid, a suitable combustion initiator, and a non-corrosive oxidizer.

15 5. A priming mixture containing a lead salt of dinitrosalicylic acid, a non-fulminate combustion initiator, and a suitable non-corrosive oxidizer.

6. A priming mixture substantially as follows:

20 Mercury fulminate..... 25% to 40%

Lead styphnate..... 5 to 10

Barium nitrate..... 24 to 44

Antimony sulphide..... 0 to 16

Normal lead dinitrosalicylate..... 4 to 10

25 Glass..... 0 to 30

7. A priming mixture containing substantially

Mercury fulminate..... 25%

Lead styphnate..... 8

Barium nitrate..... 44

80

Antimony sulphide..... 16

Normal lead dinitrosalicylate..... 7

8. A priming mixture containing basic lead nitrate, basic lead dinitrosalicylate, guanylnitrosaminoguanylterracene, and lead styphnate.

85

9. A priming mixture containing basic lead nitrate, a lead salt of dinitrosalicylic acid, and a combustion initiator.

10. A priming mixture containing basic lead nitrate, a lead salt of dinitrosalicylic acid, and basic lead picrate.

90

11. A priming mixture substantially as follows:

Lead styphnate..... 30%

Guanylnitrosaminoguanylterracene..... 2

95

Basic lead nitrate..... 30

Basic lead dinitrosalicylate..... 13

Glass..... 25
